Inventor,

William H. Walton

United States Patent Office.

WILLIAM H. WALTON, OF BROOKLYN, NEW YORK.

Letter's Patent No. 66,429, dated July 2, 1867.

IMPROVEMENT IN MACHINES FOR MAKING PAPER COLLARS.

The Schedule referred to in these Letters Patent and making part of the same:

Be it known that I, WILLIAM H. WALTON, of Brooklyn, in the county of Kings, in the State of New York, have invented certain new and useful machinery for cutting collars from paper, cloth, or other textile fabrics, which I call a "Collar-Cutting, Folding, and Rolling Machine;" and I do hereby declare the following is a full and exact description thereof, reference being had to the accompanying drawings, and to the letters of reference marked thereon.

This invention comprises the features of cutting a roll or piece of material into several strips of suitable width, from which the collars are to be cut or divided, so that each collar shall in itself be independent of the other or following collar, and thereafter guiding the cut collar to be folded and rolled in proper form, the button-holes and stitching representations being cut or imprinted as the collar passes through between the rollers, which have a rotating progressive motion. By this contrivance the collar is cut, embossed, and folded, whence it is delivered completely finished.

For the purpose more fully to illustrate my invention, I will introduce the following drawings:

Figure 1 is a side elevation, showing the positions of the strip-cutting knives, the roll of strips, and the continuous strip in its progress to the place of cutting, embossing, folding, rolling, and general delivery.

Figure 2 is a ground plan, further illustrating the position of two different parts of the machine.

Figure 3 is a sectional front view of the end of the machine at the line *a a*, as seen in fig. 2.

Figure 4 is a section of the working parts in elevation through the centre.

Figure 5 is a plan of the operating part of the machine, showing how the collars are separated from the strips of fabric.

Figure 6 is a representation of the exterior and interior folding conductors, as described.

Like letters mark the same part in all the figures of the drawings.

To enable others skilled in the art to make and use my invention, I will proceed to describe its construction and operation.

A is the main frame of the machine, and *a* is a shaft, upon which several circular knives, *r*, are mounted at such distances apart as I may desire the width of the strips to be cut, so that one wide roll of material may be cut into as many strips as desired. Said circular knives are adjustable, to cut strips of any desired width, and have a rapid revolving motion, so that when the roll of paper is placed upon the stand *b*, by the action of the hand the roll of paper may be properly presented to and evenly pressed against the knives, which sever it into as many strips as may be desired. The several rolls of strips *d d d* will next be placed on the shaft or reel *c*, one by the side of the other, as shown in fig. 5. The end of the first or front strip will then be placed between the cylinders *e* and *f*. Said cylinder *f* has a raised rib, *f'*, on its periphery, and cylinder *e* has a corresponding groove, *e'*, into which said rib on *f* fits, to form a seam in the collar where it is to be folded or turned down. The cylinder *e* is to have on its periphery surface the cutters and embossing devices, these being somewhat elevated above the surface of the main cylinder by being engraved or otherwise affixed to the main body of the cylinder. *g* is a curved cutter or knife set in cylinder *e*, with its cutting edge elevated a little above the surface of said cylinder, and its office is to shape the ends of the collars. *h* is a straight knife, set in like manner in said cylinder *e*, its edge running parallel to the axis of said cylinder, and its office is to sever one collar from another. Said knives *g* and *h* are connected, so that they will be operated by a common spring, *g'*, to regulate the pressure of said knives upon the paper and the cylinder *f*. *M* is a folding conductor, composed of two metal plates, *m'* and *L'* which are plain or flat at the ends next to the cylinders *e f*, but bent into tapering semi-tubes, so that the other ends will assume the form shown in fig. 2. The collars, after passing between the cylinders *e* and *f*, enter the narrow space between said plates, in passing through which they are folded on the crease previously formed in passing through said cylinders. From said folding conductor they are delivered to forming rollers *p p*, and in passing through said rollers they receive their finishing shape and become ready for use. Said cylinders *e* and *f* may be provided with a button-hole cutter, formed hollow in the centre, and by such devices for embossing, stamping, or indenting as may be necessary to complete the collar. The rollers *e f* draw the strip of paper forward, and at each revolution a collar is cut from the strip, forced forward through the folding conductor till its forward end is seized by the forming rollers *p p* and drawn forward by them, receiving its finishing shape as it passes between them.

The whole machinery is moved by any suitable power applied to a main shaft, B, and by means of common belts and gearing, which any competent machinist will readily understand, and which may be modified as common sense and convenience may dictate.

Having thus fully described my invention, and its mode of operation, what I claim as new, and desire to secure by Letters Patent, is—

1. In combination with the cylinders *e* and *f*, I claim the curved knife *g*, the straight knife *h*, and the spring *g'*, all constructed, arranged, and operating substantially as described.

2. I claim the folding conductor *M*, constructed, arranged in the machine, and operating substantially as described.

3. I also claim, in combination, the rollers *e f*, provided with forming and severing knives *g h*, and suitable devices for embossing or stamping, the folding conductor, and forming-rollers, all constructed and arranged substantially as described, and so geared as to make and finish collars by one continuous rotating progressive movement of machinery, forming a collar at each revolution of the said cylinders *e* and *f*.

WILLIAM H. WALTON.
